UNITED STATES PATENT OFFICE.

BENJAMIN V. KERSHNER, OF CHICAGO, ILLINOIS, ASSIGNOR TO UNION SPECIAL
MACHINE COMPANY, OF CHICAGO, ILLINOIS, A CORPORATION OF ILLINOIS.

STAY-CUTTING ATTACHMENT FOR SEWING-MACHINES.

1,169,088.

Specification of Letters Patent. Patented Jan. 18, 1916.

Application filed July 18, 1910. Serial No. 572,449.

To all whom it may concern:

Be it known that I, BENJAMIN V. KERSHNER, a citizen of the United States, residing at Chicago, in the county of Cook, State of Illinois, have invented certain new and useful Improvements in Stay-Cutting Attachments for Sewing-Machines, of which the following is a description, reference being had to the accompanying drawing, and to 10 the letters and figures of reference marked thereon.

The invention relates to new and useful improvements in stay cutting attachments for sewing machines, such as shown in the 15 patent to Coombs #456,692, granted July 28th, 1891.

An object of the invention is to improve the details of the attachment whereby the cutting action is rendered much more efficient, and whereby the tape is properly guided through the cutting attachment, and directed to the stitch-forming mechanism.

The invention consists in the parts, improvements and arrangements hereinafter 25 shown, described and set forth in the appended claims.

In the drawings which show by way of illustration one embodiment of the invention, Figure 1 is a plan view of a work support, with my attachment applied thereto. Fig. 2 is a front view of the same. Fig. 3 is a plan view from the rear of the attachment underneath the bed plate of the machine. Fig. 4 is a sectional view through the bed 35 plate and the attachment. Fig. 5 is a plan view of the attachment with the stationary shearing blade removed. Fig. 6 is a detail showing the two cutters and the guiding finger for keeping the same in proper position. Fig. 7 is a section through the two cutters.

The bed plate 1 to which my attachment is applied, may be of any desired type, and is provided with a throat plate 2 having feed slots in which the feed dog 3 operates.

As herein shown, I have provided a throat plate with two needle slots 4, 4. At the front side of the work support are two spaced raised portions 5, 5, which are cut away to form ledges 6, 6, on which rests the stationary shearing blade 7. Between the ledges 6, 6, the bed plate is further cut away to form a guiding recess through which the

stay passes on its way to the stitch forming mechanism.

A guiding loop 8 projects forwardly from 55 the side of the bed plate and the stay strip is guided underneath said loop. Located underneath the shearing blade and in the guiding recess for the tape are two edge guides 9 and 10, each of which is slotted and 60 secured to the bed plate by a suitable screw 11. The edge guides 9 and 10 are spaced so as to engage the edges of the stay strip and will direct the same properly to the feed of the machine, and the stitch forming 65 mechanism. When a wider strip is used, the screws 11 may be released and the edge guides adjusted to accommodate the same. The movable cutter 12 is held in sliding engagement with the apron 13 depending from 70 the bed plate, by a guiding plate 14. A spring 15 secured to the guiding plate 14, is bent laterally at its upper end, and projecting through a notch in the upper edge of the guiding plate 14, rests against the movable 75 knife and holds the same in close shearing contact with the stationary shearing blade. The knife 12 is beveled to form a cutting edge 16 at its upper end, and at one side of the cutting edge is a projecting finger 17 80 which remains in constant contact with the edge of the stationary shearing plate or blade. This guiding finger 17 is pressed by the spring 15 into close contact with the shearing blade, and serves as a means to 85 guide the knife when it is below the shearing blade. The stationary shearing blade 7 is slotted at 18 and the screws 19 adjustably hold said stationary blade in its seat in the work support. This stationary blade 90 may be quickly removed and ground so as to provide a very sharp cutting edge which co-operates with the movable blade. The blade may also be readily adjusted to take up the wear and the cutting away by 95 grinding.

The cutter is raised so as to shear the stay strip by a rock shaft 20, which is mounted in suitable bearings 21, 22, carried by the bed plate. A lever 23 is connected to the 100 rock shaft and is provided with suitable openings 24 to which a treadle may be attached. A spring 25 encircles the rock shaft and is connected at one end to the lever 23,

and at its other to a stud 26 secured to the bar 22. This spring is so wound as to normally hold the lever 23 raised.

A stop screw 27 limits the upward movement of the lever 23 by contact with the apron 13 of the bed plate. A lug 28 is carried by a plate 29 that is secured to the rock shaft in any desired way, so that as the rock shaft is oscillated the lug 28 moves therewith. This lug 28 is located in a recess 30 formed in the lower end of the movable cutting blade 12. The movable cutting blade is lowered or retracted by a spring 31, which is carried by a screw stud 32 and rests against the pin 33 formed in the lower end of the cutting blade. A lug 34 carried by the movable blade 12 engages the bottom of the recess formed in the guiding plate 14, and limits the downward movement of the movable knife.

The adjustable screw 27 is preferably so set that the lever 23 continues its upward movement after the blade has reached the extreme of its downward movement, and the lug 28 will be moved away from the lower end of the knife. The rock shaft 20 carries an arm 35 on which is pivoted a feed finger 36. A spring 37 is wound around the pivot screw of the feed finger and normally holds said feed finger in engagement with the under face of the stay strip. When the lever 23 is depressed, the feed finger is drawn back along the stay strip and the movable cutter 12 is raised to shear the stay strip.

When the treadle is released and the arm 23 is raised by the spring 25, the cutter will be moved downward out of the path of the stay strip, and the feed finger 26 will be moved forward, feeding a certain length of the stay strip from underneath the shearing blade, so that it may be readily caught by the feeding mechanism of the machine. A stop screw 37 engages the guiding plate 14 and limits the downward movement of the lever 23.

As clearly shown in Fig. 6, the lug 34 is tapered toward its upper end and forms a cam surface coöperating with a spring 15. When the cutter is in the position shown in Fig. 6, the pressure of the spring 15 against the movable cutter 12 is very slight. As the cutter is raised, the spring sliding along the cam surface of the pin 34 will increase the pressure, so that a maximum pressure is obtained during the time of cutting, and the pressure is released at other times, so as to relieve excessive wear on the cutters.

Having thus particularly described my invention, what I claim as new and desire to secure by Letters Patent is:—

1. In a stay cutting attachment, the combination of a movable cutting blade, a shearing blade coöperating therewith, a spring

for normally holding said movable blade retracted, a rock lever for operating said movable blade, a feeding finger operated by said rock lever, and an independent spring for controlling said rock lever.

2. In a stay cutting attachment, the combination with a stationary shearing blade underneath which the tape is guided, a movable cutting blade coöperating with said stationary blade, a spring for depressing said movable blade, a stop for limiting the downward movement of said blade, a rock lever for raising said blade, a spring for moving said rock lever in a direction to release the movable blade and a stop for limiting the movement of said rock lever by said spring.

3. In a stay cutting attachment, the combination of a movable cutting blade, a shearing blade coöperating therewith, a spring for normally holding said blades in contact, and means located on the opposite side of the material from the shearing blade whereby the spring pressure of one blade against the other is increased as said movable cutting blade moves forward to perform its cutting action, and means for operating said movable cutting blade.

4. In a stay cutting attachment, the combination of a movable cutting blade, a shearing blade coöperating therewith, a spring for pressing said movable cutting blade against the shearing blade, a tapered pin carried by said movable blade and adapted to be engaged by said spring for increasing the spring pressure of the movable blade against the shearing blade as the movable blade moves forward for its cutting action, and means for operating said movable cutting blade.

5. In a stay cutting attachment, the combination of a movable cutting blade, a shearing blade coöperating therewith, a spring for pressing said movable cutting blade against the shearing blade, a tapered pin carried by the movable blade and adapted to be engaged by said spring for increasing the spring pressure of the movable blade against the shearing blade as the movable blade moves forward for its cutting action, a spring for normally retracting said movable cutting blade, means coöperating with said tapered pin for limiting the retracted movement of said blade, and means for moving said blade for its cutting action.

6. In a stay cutting attachment, the combination of a movable cutting blade, a shearing blade coöperating therewith, a spring for pressing said movable cutting blade against the shearing blade, a tapered pin carried by said movable blade and adapted to be engaged by said spring for increasing the spring pressure of the movable blade against the shearing blade as the movable blade moves forward for its cutting action,

means for operating said movable cutting blade, and a feeding finger operating to feed the stay between the cutting blades when the same are separated, said feeding finger
5 being actuated by means for operating said movable cutting blade.

In testimony whereof I affix my signature in presence of two witnesses.

BENJAMIN V. KERSHNER.
